UNITED STATES PATENT OFFICE.

BERNARD LUTSKY AND SIMON KREISBERG, OF BROOKLYN, NEW YORK.

LIQUID-DISPENSING FAUCET.

Application filed September 24, 1925. Serial No. 58,300.

To all whom it may concern:

Be it known that we, BERNARD LUTSKY and SIMON KREISBERG, both citizens of the United States, and residents of the borough 5 of Brooklyn, county of Kings, city and State of New York, have invented certain new and useful Improvements in Liquid-Dispensing Faucets, of which the following is a specification sufficient to enable those skilled in the art to which the invention 10 appertains to utilize the same.

Our improvements relate to the class of liquid supply faucets, designed primarily for the dispensing of beverages, in which a 15 receptacle, such as a drinking glass or the like, is utilized as a means of actuating the parts by which the valve is opened to effect the discharge of the required liquid, the valve being closed automatically upon the 20 removal of said receptacle; and are designed to afford a simple, compact and effective combination and arrangement of parts whereby these results are attained under sanitary 25 conditions, and whereby ample provision is made for adjustment and regulation of flow, all as hereinafter fully set forth,—the invention consisting in the specific construction of faucet and component parts 30 thereof described and claimed.

The accompanying drawings illustrate a practical embodiment of the essential features of the invention in a dispensing faucet of the character designated, although we do not limit ourselves to the identical form 35 and construction of component parts herein shown by way of exemplification, since changes may be made in minor details, and equivalent mechanical expedients resorted to, with like results, and without departing 40 from the spirit and intent of our invention in this respect.

With this understanding:

Fig. 1, represents a side elevation of our improved liquid dispensing faucet in normal position;

Fig. 2, a like view with the actuating rock lever retracted by contact with a receptacle for the liquid discharge;

Fig. 3, is a front elevation of the faucet;

Fig. 4, is a central vertical sectional elevation thereof, taken mainly on plane of line 4—4, Fig. 3;

Fig. 5, is an elevation of the nozzle member;

Fig. 6, is an elevation of the upper end of said nozzle member; and

Fig. 7, an elevation of the lower or discharge end of said nozzle member;

Fig. 8, is an elevation of the valve stem;

Fig. 9, is an elevation of the spout member; and

Fig. 10, is an end view thereof.

The base of the service bracket pipe B, is adapted for attachment to a connection with a source of supply of the liquid to be dispensed, its upper extremity being screw threaded for unitary engagement with the head piece or casing A, in which the supply duct a, and outlet port a', are located, as shown more particularly in Fig. 4, of the drawings; the area of communication between said duct a, and said port a', being prescribed and regulated by means of an adjustable screw a^x. That is to say, the inner lower end of said screw a^x, is interposed between said supply duct a, and said outlet port a', so that it functions to limit the flow of liquid to and through said port a'. 60

The upper end of this adjustable screw a^x, is nicked for engagement with a screw driver or like manipulative implement, and is enclosed and protected by a screw cap a².

The under side of the head casing A, is recessed to form a valve chamber a³, below and communicating with the outlet port a', and this recess is female screw threaded for the reception of the male threaded upper extremity of the spout member S, thereby uniting said spout S, integrally with the head casing A. The upper portion of the spout S, is formed with a shouldered recess s, for the reception and support of an annular rubber or equivalent packing s', which constitutes the seat for the valve V, the stem v, of which is male screw threaded at 70 its lower extremity for engagement with a corresponding female screw thread formed for the purpose in the upper end of the cylindrical nozzle N, the upper portion of which latter fits within the cylindrical recess s², in the lower portion of the spout S. Interposed between a shoulder s³, in the spout S, and the upper end of the nozzle N, is a coiled spring s⁴, which tends constantly to 75 press the nozzle N, downward with its external annular conoidal shoulder n, in contact with the arms r, r, of the loop cam r', forming an integral part of the rock lever R. The upper, and otherwise solid portion 80 of the nozzle N, is formed with a plurality of convergent ducts n', n', which establish communication between the pressure cham-

ber s^2 , in the spout S, above the upper end of the nozzle N, and its discharge passage n^2 .

The bifurcated upper end of the rock lever R, is pivotally supported upon the head casting A, by fulcrum screws f , f , upon and by which said rock lever R, is suspended, and is retractile against the resistance of the spring s^4 , acting through the medium of the nozzle member N, and its conoidal shoulder n ,—the upwardly curved side arms r , r , of the said loop cam r' , during such retractile movement of the rock lever forcing the nozzle N, upward against the resistance of said spring s^4 , and thereby raising the valve V, from its seat s' , and admitting liquid to the pressure chamber s^2 ,—this retractile movement of the rock lever R, being limited by the end (r') of the loop cam, as indicated in Fig. 2, of the drawings.

When the rock lever R, is released from extraneous pressure, as by the withdrawal of the drinking glass G, or equivalent liquid receptacle, the operative parts are again returned to normal positions by the spring s^4 , which thus functions in a double capacity,—i. e. as a valve closer and manipulative lever control.

The lower extremity of the said manipulative rock lever R, is also bifurcated to form a concave terminal bearing r^2 , for contactual engagement with the convex sides of the receptacle G, and this bearing r^2 , is preferably provided on its concave surface with buffers r^3 , r^3 , of soft material.

The lower end of the valve stem v, being screw-threaded, and thus adjustable upon the nozzle member N, it is obvious that the play of the valve V, with relation to its seat s' , may be regulated with accuracy according to requirements; and this feature, in conjunction with the regulation of inlet area by the adjustable screw a^x , affords ample variation for all practical purposes of adaptability to circumstances and conditions of use of our liquid dispensing faucet, considered in a unitary sense.

Furthermore, our device is not only essentially automatic and sanitary in operation, but is also simple and compact in structure, and conveniently accessible for purposes of cleansing or renewal of parts.

What we claim as our invention and desire to secure by Letters Patent, is:—

1. In a liquid dispensing faucet of the character designated, the combination of a spout member, formed with a valve seat, a nozzle member slidably mounted within said spout member, a valve adjustably mounted on said nozzle member, a coiled spring interposed between said nozzle member and said spout member, and a manipulative rock lever formed with cam means, engaging with said slidable nozzle member, substantially in the manner and for the purpose set forth.

2. In a liquid dispensing faucet of the character designated, the combination of a spout member formed with a valve seat, means for regulating the flow of liquid thereto, a nozzle member slidably mounted within said spout member, a valve adjustably mounted on said nozzle member, a coiled spring interposed between said nozzle member and said spout member, and a manipulative rock lever formed with cam means, engaging with said slidable nozzle member, substantially in the manner and for the purpose set forth.

3. In a liquid dispensing faucet of the character designated, the combination of a spout member formed with a valve seat, means for regulating the flow of liquid thereto, a nozzle member slidably mounted within said spout member, a valve adjustably mounted on said nozzle member, a coiled spring interposed between said nozzle member and said spout member, and a manipulative rock lever formed with a cam loop for engaging with said slidable nozzle member, substantially in the manner and for the purpose set forth.

BERNARD LUTSKY.
SIMON KREISBERG.
